UNITED STATES PATENT OFFICE.

SAMUEL HAYWARD, OF BOSTON, MASSACHUSETTS.

DESIGN FOR CHAIRS.

Specification forming part of Design No. 6,828, dated August 26, 1873; application filed June 30, 1873.

To all whom it may concern:

Be it known that I, SAMUEL HAYWARD, of Boston, in the county of Suffolk and State of Massachusetts, have invented a new and useful Design for a Chair-Frame, of which the following is a specification:

My invention relates, in the first place, to the general shape or outline of the chair-frame, which gives it its distinctive feature as compared with other chair-frames, without particular reference to the exact ornamentation applied thereto; and it relates, in the second place, to the combination, with a chair-frame of the shape or outline shown, and the arrangement thereon, of certain carved moldings, beads, rosettes, scrolls, blocks, drops, &c., as will be more fully described.

A A represent the side frames of the chair, each consisting of two legs, a a, the back standard b, and the scroll-arm c, each radiating from a common center (though not in straight lines) at or near the point of attachment to the seat. B is the seat-frame, secured to the two sides, and projecting in front of the scroll-arms c c, as shown. C is the head girt, and D the middle girt, connected at C, so as to form a frame, to be upholstered to form the back. The upper ends of the back standards b b terminate in small scrolls, turned toward the front of the chair, with rosettes b' b' on either side thereof. The front ends of the sides of the seat-frame B also terminate in scrolls, turned downward, as shown. Upon either side of the scroll-arms c c are rosettes d, or other suitable circular ornaments, from which springs the molding e e, running around the

edge of the scroll-arm c till it is intercepted by the block f, from the opposite side of which it is continued, turning downward upon the side of the frame A, and terminating in a small scroll, g. Upon the outside of each frame A, in the center of the upright portion thereof, is placed the drop h, dependent from the scroll g. The upper side of the arm, in the rear of the block f, and the front of the standards b, are ornamented with a bead or molding, i, running along both sides thereof, and a leaf, j, carved upon the upper face of the same. The legs a a terminate in carved ornamental feet, as shown and described.

The ornamentation shown is of the Grecian pattern; but a different style of ornamentation may be used without materially changing the general effect of the design as it strikes the eye.

What I claim as my invention is—

1. The design of the outline shape of the chair-frame, substantially as shown.
2. The design of the combined outline shape and the carved ornamentation, consisting of the rosettes b' and d, the block f, scroll g, the drop h, the connecting moldings e and i, and the leaves j, disposed and arranged as set forth and shown, with or without the carved feet on the legs a a, substantially as shown and described.

Executed at Boston this 20th day of June, 1873.

SAMUEL HAYWARD.
